UNITED STATES PATENT OFFICE.

JONAS A. TAUTPHAEUS, OF SAPPINGTON, MISSOURI.

VEHICLE-BRAKE.

SPECIFICATION forming part of Letters Patent No. 708,272, dated September 2, 1902.

Application filed March 24, 1902. Serial No. 99,655. (No model.)

To all whom it may concern:

Be it known that I, JONAS A. TAUTPHAEUS, a citizen of the United States, residing at Sappington, in the county of St. Louis and State 5 of Missouri, have invented certain new and useful Improvements in Vehicle-Brakes, of which the following is a full, clear, and exact description, reference being had to the accompanying drawings, forming part of this 10 specification.

My invention relates to a brake adapted for use upon spring-wagon or other spring-vehicles, the object of the invention being to provide a construction of brake carried by the 15 running-gear of a spring-vehicle that is simple and durable and one that is easily and effectively applied to the wheels of the vehicle.

My invention consists in features of novelty hereinafter fully described, and pointed 20 out in the claims.

Figure I is a view, partly in elevation and partly in longitudinal section, of a wagon with my brake shown applied thereto in elevation. Fig. II is a perspective view of the 25 brake. Fig. III is an enlarged detail view, partly in plan and partly in horizontal section, taken on line III III, Fig. II. Fig. IV is an enlarged detail view illustrating the manner of attachment of the rock-shaft of the 30 brake to the vehicle.

A designates the wheels of a vehicle, in which are mounted the axles B, as usual.

C is the vehicle-bed, and D represents the springs on which the bed is mounted.

35 1 designates a hanger swingingly suspended in boxes 2, fixed to the vehicle-bed C in a position forward of the rear vehicle-wheels. The hanger 1 is formed of a continuous piece of material and comprises a horizontal portion which is secured to the body of the vehicle and at each end of which is a depending portion, while the extreme ends of the hanger are outturned, as seen in Fig. II, and loosely mounted on these outturned ends 3 40 of the hanger are the brake-heads 4.

5 designates a rock-shaft mounted in the seats 6 of the rear vehicle-springs D or otherwise suitably supported in proximity to the rear vehicle-axle. This rock-shaft 5 is provided with downwardly-extending arms 7 and 8, that receive the pivotal connection of the lower ends of pull-rods 9, the forward ends of

which extend to the brake-heads 4. Each pull-rod 9 is provided at its forward end with an eye 10, that is fitted to the outturned ends 55 3 of the swinging hanger 1.

11 represents eyebolts seated in the brake-heads 4 and in which the pull-rods 9 are loosely mounted. These eyebolts serve to hold the brake-heads in upright position, so 60 that they are presented to the adjacent wheels of the vehicle to be drawn thereagainst in the movement of the pull-rods.

12 is a lever-arm carried by the rock-shaft 5 and to which is attached the brake-rod 13, 65 that leads to the brake-lever 14.

In the practical use of the brake herein described the parts are operated upon the movement of the brake-lever 14, which when moved in a forward direction causes a pull to be exerted upon the brake-rod 13 to rock the rock-shaft 5. On the movement of the rock-shaft its arms 7 and 8 are thrown rearwardly and the brake-heads are moved to the vehicle-wheels, their movement being freely permitted 70 by the swinging hanger 1, on which they are mounted. The brake is entirely mounted upon the running-gear of the vehicle, and therefore all its parts are firmly sustained in their working positions, so that their service 75 80 may be performed effectually on a spring-vehicle and in a manner unaffected by the movement of the vehicle-body, such as is incident to brakes carried by the body of the vehicle.

While I have shown the rock-shaft 5 as 85 mounted in the seat 6 at the rear of the vehicle-springs, I do not wish to be understood as limiting myself to so mounting the rock-shaft, as it may be loosely supported in the clips that connect the springs to the rear vehicle- 90 axle, as I have shown in dotted lines, Fig. IV.

I claim as my invention—

1. In a vehicle-brake, the combination with a hanger, of a pull-rod loosely connected to the hanger, and a brake-head loosely pivoted 95 to the hanger, of an eyebolt seated in the brake-head and in which the pull-rod is positioned to provide a connection between pull-rod and brake-head independently of the hanger.

2. In a vehicle-brake, the combination with a swinging hanger, suspended from the wagon-body, formed of a continuous piece of material, and comprising a horizontal portion, a

depending portion at each end of the horizontal portion, and outturned ends; of brake-heads carried by the outturned ends of the hanger, a rock-shaft carried by the running-
5 gear, pull-rods secured to the outturned ends of the hanger between the brake-heads and the depending portion, and connecting with

the rock-shaft, eyebolts secured in the brake-heads and receiving the pull-rods, and means for operating the rock-shaft.

JONAS A. TAUTPHAEUS.
